UNITED STATES PATENT OFFICE.

WILLIAM H. F. YOUNG, OF MUNCIE, INDIANA.

LOCK AND LATCH.

1,112,347.

Specification of Letters Patent. Patented Sept. 29, 1914.

Application filed February 12, 1913. Serial No. 747,970.

To all whom it may concern:

Be it known that I, WILLIAM H. F. YOUNG, a citizen of the United States, residing at Muncie, in the county of Delaware and State of Indiana, have invented certain new and useful Improvements in Locks and Latches, of which the following is a specification, reference being had therein to the accompanying drawing.

10 My invention relates to improvements in locks and latches, and is an improvement on my Patent No. 1,025,850.

The object of my invention is to provide a combined lock and latch used on doors and similar structures, which may be more readily applied to the door and is adapted to adjust itself whereby the escutcheon plate rests against the side of the door, as in the usual form of locks.

20 Another object of my invention is to provide a lock of this type in which the knob and all other parts of the lock are carried by the escutcheon plate and which may be more readily applied to the door.

25 A still further object of my invention is to provide means whereby the bolt may be held in its outward or retracted position to prevent it from being moved and also to provide a positive locking means whereby the bolt may not be forced inwardly by pressure at the outer end thereof.

In the accompanying drawings: Figure 1 is a horizontal longitudinal sectional view of my improved invention. Fig. 2 is a vertical sectional view taken at right angles to Fig. 1. Fig. 3 is a vertical sectional view similar to Fig. 2, showing the latch and bolt in their retracted position. Fig. 4 is a transverse vertical sectional view taken on a line 4-4 of Fig. 2. Fig. 5 is an enlarged perspective view of the bolt locking pawl. Fig. 6 is an inverted perspective view of the locking pawl for locking the bolt in its upward position against inward movement.

45 Referring now to the drawings, 1 represents the outer edge of the door in which is mortised the face plate 2 of the lock. The face plate 2 is secured to the escutcheon plate 3, by means of screws 4, passing through the laterally turned ears 5, carried thereby. The said face plate is of a width greater than that of the door, and as shown in Fig. 1, extends beyond the face of the door. Carried by the inner face of the face plate 2 is the barrel 6, in which the lock proper is located.

55 In locks of the character to which my in-

vention relates, it is understood by those skilled in the art that the latch 7 slides within the bolt 8, and both the bolt and the latch are adapted to be operated by the inside 60 knob 9. The latch 7 is also retracted by the outside knob 10, the same as the ordinary lock now in use. The bolt, however, is not retracted by the outside knob, but is operated by the key 11, which in turn operates 65 the key spindle 12, all of which needs no further description as this is shown and described in my Patent No. 1,025,850, heretofore referred to.

The dead bolt operating disk 13 of my improved lock, as clearly shown in Fig. 2 of the drawing, is provided with two recesses 14 and 15 arranged in an arc of a circle and into which fits a spring pressed ball 16, mounted in a circular housing 17, carried by 70 the inner face of the barrel 6. When the bolt 8 is in its inward position, it will be seen that the ball 16 is in the recess 14, carried by the plate 13, and when the bolt is retracted, the ball rides out of the recess 14 and travels 75 over the face of the disk and enters the recess 15, whereby the bolt is frictionally held in either position. In order that the bolt 8 cannot be operated by pressure at its outer end, as often results in locks of this character when they are forced by a sharp instrument, I provide my improved attachment. 80 This attachment, as shown in Fig. 1 of the drawings, consists of a member 18, and is secured to the inner end of the bolt 8 by 85 means of a screw 19, passing through an elongated opening 20 which allows the same to have a longitudinal movement on the bolt. The outer end of the member 18 is provided with a downwardly extending arm 21, which 90 engages the outside face of the bolt and forms a guide to prevent any lateral movement thereof.

The upper face of the member is provided with a transverse lug 22, having a straight 100 vertical front wall 23, and a beveled rear wall 24. The inner face of the barrel 6 is provided with ears 25, between which is pivoted a pawl 26, which is adapted to slide upon the outer face 27 of the member 18. 105 The pawl 26 is held in an inward position by means of a leaf-spring 28, which bears against the outer face thereof. The outer end of the pawl is slightly enlarged and is provided on its inner face with a recess 29, 110 which is provided with a vertical outer wall 30, and a beveled inner wall 31, to correspond

with the straight face 23 and beveled face 24 of the lug 22 carried by the member 18.

The bolt 8, as shown in Fig. 1 of the drawings, is provided with a cutaway portion 32, into which the outer end of the pawl passes. The vertical wall 30 of the pawl engages the outer straight wall of the cutaway portion 32, and any pressure on the outer end of the bolt will cause the pawl to more tightly engage the bolt and it is impossible to move the same inwardly. The slot connection between the member 18 and the bolt allows the bolt to move inwardly a slight distance without moving said member, whereby the engagement between the bolt and pawl is tightened. Any inward movement of the bolt by means of the knob mechanism, or the key mechanism, will cause the member 18 to move before the bolt 8 begins to move which by means of the beveled wall 24 of the lug 22, lifts the pawl 26 before the outer end engages the wall of the cutaway portion and thus the bolt is free to move inwardly by a pull on the bolt. The beveled wall 24 of the lug also raises the pawl and allows the bolt to be forced outwardly by the key or knob mechanism.

The key spindle 12 is extended inwardly as indicated at 34 and enters a square sleeve 33 carried by the spindle 9' of the inside knob 9. This key spindle 12 operates the sleeve 38, which in turn operates the member 39 carrying the disk 40, which engages the lugs 41 and 42 of the sliding bolt 8 and whereby the bolt and latch are moved inwardly by the inside knob.

Having thus described my invention, what I claim and desire to secure by Letters Patent is:

40. 1. In a lock of the character described, the combination with a bolt, a disk for operating said bolt and a spring pressed ball engaging the disk for frictionally holding it in its adjusted position.

45. 2. In a lock of the character described, the combination with a sliding bolt, a disk having recesses in one face thereof, a spring pressed ball engaging the disk and adapted to enter the recesses, whereby the bolt is frictionally held in its outward or retracted position.

50. 3. In a lock of the character described, the combination with a sliding bolt, of the

disk for operating the said bolt, the outer face of the disk having two recesses arranged in a circular line, a housing adjacent the disk and a spring pressed ball within the housing and adapted to engage the face of the disk and enter the recesses therein, whereby the bolt is held in its outer or retracted position.

4. In a lock of the character described, the combination with a sliding bolt, a disk for operating the said bolt, the outer face of the disk having recesses arranged in a circular line, a housing adjacent the disk, a spring pressed ball within the housing, adapted to engage the face of the disk and enter the recesses carried thereby, whereby the bolt is frictionally held in its outer or retracted position.

5. In a lock of the character described, the combination with a sliding bolt, of a disk for operating the said bolt and having recesses in its outer face, a housing adjacent the disk, a spring pressed ball within the housing and adapted to enter the recesses in the face of the disk, and a spring pressed pawl for locking the bolt in its outward position against inward movement by pressure at the outer end of the bolt.

6. In a lock of the character described, the combination with a sliding bolt, of a disk, a spring pressed ball within the housing and engaging the disk for frictionally holding it in its adjusted position, a latch carried by the bolt and a pawl engaging the latch and holding the bolt in its outward position against inward movement by the pressure at the outer end and allowing the bolt to be readily withdrawn by an inward pull at its inner end.

7. In a lock of the character described, the combination with a sliding bolt, a disk for operating the said bolt, a spring pressed ball engaging the disk and frictionally holding it in its adjusted position, whereby the bolt is held in its inward or outward position.

In testimony whereof I hereunto affix my signature in the presence of two witnesses.

WILLIAM H. F. YOUNG.
